DESIGN FOR A FORTUNE TELLER'S BOB

Carmen A. Buds, Stamford, Conn.

Application March 2, 1938, Serial No. 75,525

Term of patent 7 years

To all whom it may concern:

Be it known that I, Carmen A. Buds, a citizen of the United States, residing at Stamford, in the county of Fairfield and State of Connecticut, have invented a new, original, and ornamental design for a Fortune Teller's Bob, of which the following is a specification, reference being had to the accompanying drawing, forming part thereof.

Fig. 1 is a front view of my fortune teller's bob.

Fig. 2 is a section taken along lines 2—2 of Fig. 1. Fig. 3 is a rear view of my fortune teller's bob, while Fig. 4 is a sectional view along line 4—4 in Fig. 1.

I claim:

The ornamental design for a fortune teller's bob, substantially as shown.

CARMEN A. BUDS.
